WOMAN'S BLOUSE

Erwin B. Jackman, Brooklyn, N. Y.

Application February 2, 1955, Serial No. 34,333

Term of patent 7 years

(Cl. D3—4)

The figure is a plan view of a woman's blouse in undraped position showing my new design. Both faces of the blouse are identical in appearance.

I claim:

The ornamental design for a woman's blouse, substantially as shown and described.
